Primary Examiner — Rebecca Tsehay*(74) Attorney, Agent, or Firm* — BakerHostetler**CLAIM**

The ornamental design for a bracket for an electronic cigarette, as shown and described.

DESCRIPTION

FIG. 1 is a front view of a bracket for an electronic cigarette; FIG. 2 is a rear view thereof; FIG. 3 is a left side view thereof; FIG. 4 is a right side view thereof; FIG. 5 is a top view thereof; FIG. 6 is a bottom view thereof; FIG. 7 is a front isometric view thereof; and, FIG. 8 is a rear isometric view thereof.

The broken lines in the drawings depict portions of the bracket for electronic cigarette that form no part of the claimed design.
